CLAIM

The ornamental design for a hand-mounted phallus retention panel, as shown and described.

DESCRIPTION

FIG. 1 is a perspective view of the hand-mounted phallus retention panel;

FIG. 2 is a view in right side elevation of the hand-mounted phallus retention panel of FIG. 1;

FIG. 3 is a view in left side elevation of the hand-mounted phallus retention panel of FIG. 1;

FIG. 4 is a top plan view of the unfolded hand-mounted phallus retention panel of FIG. 1;

FIG. 5 is a bottom plan view of the unfolded hand-mounted phallus retention panel of FIG. 1;

FIG. 6 is a view in front elevation of the hand-mounted phallus retention panel of FIG. 1;

FIG. 7 is a view in rear elevation of the hand-mounted phallus retention panel of FIG. 1; and,

FIG. 8 is a perspective view of the hand-mounted phallus retention panel of FIG. 1 retaining a phallus and applied to a hand.

The broken lines shown in the drawings represent environmental subject matter and form no part of the claimed design.
